UNITED STATES PATENT OFFICE.

JOHN C. KONRAD, OF NEW YORK, N. Y., ASSIGNOR TO CLARENCE WAINRIGHT WOOD, OF SAME PLACE.

DESIGN FOR A BODY FOR DELIVERY-WAGONS.

SPECIFICATION forming part of Design No. 28,749, dated May 31, 1898.

Application filed February 19, 1898. Serial No. 670,975. Term of patent 7 years.

To all whom it may concern:

Be it known that I, JOHN C. KONRAD, a citizen of the United States of America, and a resident of the borough of Manhattan, in the city of New York and State of New York, have invented and produced a new and original Design for a Body for Delivery-Wagons, of which the following is a specification, reference being had to the accompanying drawing, forming part thereof.

The figure of the drawing is a side view of the body of a delivery-wagon, showing said new and original design.

The leading or material feature of this design is the shape or configuration of the front portion of the wagon-body in side view. The shape of said front portion comprises a substantially horizontal roof-line 1, a vertical border member 2, common to the front and rear portions, an ornate corner-brace 3 beneath the roof, filling the angle between said roof-line and the front line of said vertical border member, the main feature of which is a semioval concavity in its front edge having its border raised with reference to the body

of the brace and ornamented by recurved ends *a* and a central bilabiate projection *b*, a curved seat-arm and seat-front border member 4, having an inturned bilabiate ornament *c*, and a simple curvilinear arch 5 beneath the seat, having a border which, together with said border members 2 and 4, incloses a panel 6 of irregular outline. Border members 7, 8, and 9, together with said border member 2, inclose a substantially rectangular side panel 10 in rear of said front portion and are shaped with substantially square outer angles *d* and inturned bilabiate corner-ornaments *e*. An oval lamp-window is represented at 11, and supplemental penciled stripes on the respective panels at 12 and 13.

Having thus described said design, I claim as new and original and desire to patent under this specification—

The design for the body of a delivery-wagon, substantially as shown and described.

JOHN C. KONRAD.
